CLAIM

The ornamental design for a bottle, as shown and described.

DESCRIPTION

FIG. 1 is a perspective view of a bottle showing my new design;

FIG. 2 is a front elevation view thereof;

FIG. 3 is a right side elevation view thereof;

FIG. 4 is a top plan view thereof with the opposing side details seen through the transparent surface not being shown for ease of illustration; and,

FIG. 5 is a bottom plan view thereof, with the opposing side details seen through the transparent surface not being shown for ease of illustration.

The rear side of the design is a mirror image of the front side, and the left side of the design is a mirror image of the right side. The broken lines in the drawings illustrate the portions of the bottle that form no part of the claimed design.
